[57] CLAIM

The ornamental design for a front face of a confectionery package, as shown and described.

DESCRIPTION

FIG. 1 is a top plan view of a front face of a confectionery package embodying my design; and,

FIG. 2 is a top plan view of a second embodiment thereof. The front face of a confectionery package is of no appreciable thickness and the undisclosed bottom plan view is unornamented.

The broken lines shown in FIGS. 1 and 2 are for the purpose of showing environmental structure only and form no part of the claimed design.
